DESIGN FOR A WHEEL BODY

Charles W. Sinclair, Detroit, Mich., assignor to
Kelsey-Hayes Wheel Company, Detroit, Mich.,
a corporation of Delaware

Application October 14, 1935, Serial No. 58,974

Term of patent 14 years

To all whom it may concern:

Be it known that I, Charles W. Sinclair, a citizen of the United States of America, residing at Detroit, in the county of Wayne and State of Michigan, have invented a certain new, original, and ornamental Design for a Wheel Body, of which the following is a specification, reference being had therein to the accompanying drawing, forming a part thereof, in which Figure 1 is a perspective view of a wheel body embodying

my new design; Figure 2 is a fragmentary elevation of the wheel body; Figure 3 is an axial profile thereof; and Figure 4 is a transverse spoke section.

The dominant feature of the design is indicated in solid black lines.

I claim:

The ornamental design for a wheel body substantially as shown and described.

CHARLES W. SINCLAIR.
